COMBINATION LIPSTICK AND BLENDER

Margaret Belle Jones, Hickman Mills, Mo.

Application March 7, 1938, Serial No. 194,491

3 Claims. (Cl. 132—79)

This invention relates to toilet articles in the nature of a lipstick and blender holder that may be carried in the purse and which is unitary in form so that both the lipstick and blender are available through the handling of but one element and its cover.

One of the important aims of the instant invention is the provision of a combination lipstick and blender both of which are housed in a specially formed case in a fashion so as to be projected therefrom singly or simultaneously so that after the lipstick is used, spreading and outlining may take place through the employment of the blender while the lipstick per se, is completely housed in that portion of the case partitioned off for its reception.

It is well known in the art that the use of the fingers or an instrument which is not maintained in a sanitary condition to spread and outline the rouge after it has been applied, is unsanitary and dangerous because of the possibility of infection resulting from the application of germs directly to the lips by the fingers or such aforesaid instrument. It is desirable therefore, to completely encase the blender which is to be used with the lipstick while it is not in operation, and since the employment of the blender occurs directly after using the lipstick, it is preferable to enclose the two elements in a specially created case that is provided with structure for projecting either one of the elements from the case to an operative position, both elements being simultaneously projected if desired.

Another object of the invention includes the provision of uniquely arranged finger plates which are struck or otherwise provided on the holders for the lipstick and blender, that project outwardly through slots in the case and notches in the cover in such a way as to insure that the lipstick and blender are completely housed within the case when the cover therefor, is in its normal position.

Minor objects of the invention, including specific details of construction will appear during the course of the following specification, referring to the accompanying drawing where'n:

Figure 1 is a perspective view of a combination lipstick and blender made to embody the present invention.

Fig. 2 is a longitudinal central section through the device.

Fig. 3 is a perspective view of the case forming a part of the device showing the cover entirely removed therefrom.

Fig. 4 is a cross sectional view taken on line IV—IV of Fig. 2; and,

Fig. 5 is an enlarged fragmentary elevation of the portion of the device showing the relation between the parts as the cover is moved over the upper portion of the case.

The case 6 of this device is made of any suitable material and formed so as to present a pair of opposed side walls 8 and opposed edge walls 10. A bottom 12 having a shoulder 14 formed thereon, 10 closes one end of case 6 and a transverse partition 16 divides the interior of case 6 into a compartment 18 and a compartment 20. Each edge wall 10 has a slot 22 provided therein that extends longitudinally along the medial line of wall 10 and 15 terminates short of the ends of walls 10.

Compartment 18 may receive blender 24. This blender is made of tightly compacted fibrous material that presents a stick-like body having a dome shaped head 26. The other end of blender 20 24 extends into a cup 28 that has ears 30 struck therefrom, to project through slot 22 formed in the proximal edge 10 of case 6. These ears 30 project far enough beyond the outer face of wall 10 to pass through notch 32 formed in cover 34. 25

A plate 36 is secured to the projected ends of ears 30 and extends laterally to each side of ears 30 to provide overhanging flanges 38 that engage the outer surface of cover 34 when the same is in place.

Lipstick 40 is of the conventional type and character, and is held by a cup 42 that slides longitudinally along compartment 20. This cup 42 like cup 28, has a pair of ears 44 struck therefrom, and a plate 46 secured thereto in precisely 35 the same manner as set down with respect to plate 36. Overhanging portions 48 of plate 46 are practically against the outer face of cover 34 when the device is assembled.

Cover 34 is slightly longer than case 6 and a 40 notch 32 is formed in each of the two opposed side walls thereof. Notches 32 are much shorter than slots 22 so that after the rouge and blender have been used, placing the cover in the normal position will force these elements 40 and 24 45 respectively, back into their compartments 20 and 18 by cover 34. The edge of cover 34 engages shoulder 14 of bottom 12 as the bottoms of cups 28 and 42 reach the inner face of bottom 12.

A slit 50 extends longitudinally from one end of each slot 22 so as to set off a pair of ears 52, the outer faces of which are spaced apart a distance about the same as the distance between longitudinal edges of cover 34 forming notch 32. 55

These ears 52 are out-turned and the upper ends are arcuate so that as cover 34 is moved to position, the ears guide notch 32 to a straddling relation with respect to ears 38 and 44 of cups 28 and 42 respectively. After the inner end of notch 32 is reached, a frictional engagement is had with the inner faces of opposed walls of cover 34 in which are formed notches 32, thus there is provided a frictional engagement between case 6 and cover 34 which is easily overcome by the operator, yet avoids accidental displacement.

It is understood that a combination lipstick and blender embodying this invention, might be made to present a physical appearance other than that illustrated in the accompanying drawing and therefore, it is desired to be limited only by the scope of the appended claims.

Having thus described the invention, what is claimed as new and desired to be secured by Letters Patent is:

1. A device of the character described comprising an open-end case having a central longitudinal partition dividing the case into two compartments and provided with longitudinal slots in opposed walls of the case; a cup slidably mounted in each compartment respectively; laterally extending fingers on the cups projecting through the slots in the case; a cover adapted for full telescoping engagement with the case and provided with notches in opposed sides thereof; and laterally extending ears on the said opposed walls of the case disposed to first enter the notches in the cover, then frictionally engage the inner faces of said opposed sides of the cover as the latter is moved to a normal position on the case.

2. A device of the character described comprising an open-end case having a central longitudinal partition dividing the case into two compartments and provided with longitudinal

slots in opposed walls of the case; a cup slidably mounted in each compartment respectively; laterally extending fingers on the cups projecting through the slots in the case; a cover adapted for full telescoping engagement with the case and provided with notches in opposed sides thereof; and a pair of spaced apart, parallel, laterally extending ears on each of the opposed walls of the case disposed to first enter the notches in the cover then to frictionally engage the inner faces of said opposed sides of the cover as the latter is moved to a normal position over the case, the distance between the outer faces of said ears being substantially the same as the width of said notches and the width of said laterally extending fingers on the cups.

3. A device of the character described comprising an open-end case having a central longitudinal partition dividing the case into two compartments and provided with longitudinal slots in opposed walls of the case; a cup slidably mounted in each compartment respectively; laterally extending fingers on the cups projecting through the slots in the case; a cover adapted for full telescoping engagement with the case and provided with notches in opposed sides thereof; and a pair of spaced apart, parallel, laterally extending ears on each of the opposed walls of the case disposed to first enter the notches in the cover then to frictionally engage the inner faces of said opposed sides of the cover as the latter is moved to a normal position over the case, the distance between the outer faces of said ears being substantially the same as the width of said notches and the width of said laterally extending fingers on the cups, said ears having arcuate free edges formed to gradually force apart the opposed sides of the cover as it is moved over the case toward the normal position.

MARGARET BELLE JONES.
